YARN-WINDING APPARATUS

Stephen Miller Fulton and William Harry Kimp-ton, Spondon, near Derby, England, assignors to Celanese Corporation of America, a corporation of Delaware

Application November 23, 1937, Serial No. 176,006
In Great Britain December 1, 1936

19 Claims. (Cl. 242—35.5)

The invention relates to yarn-winding apparatus of the type in which completed pirns, cops, spools or like packages (hereinafter referred to for brevity as "pirns") are automatically removed from a machine and replaced by fresh package supports on which the winding of new pirns continues, the automatic pirn-replacing enabling such machines to run for long periods without attention.

10 It is an object of the invention so to improve such machines that they require still less attention.

According to the invention there is incorporated in a pirn-winding machine of the type referred to a counting device adapted to be actuated at each pirn-winding operation, and means controlled by the counting device and adapted automatically to render the pirn-replacing mechanism inoperative after a predetermined number 20 of pirns have been wound. In this manner the pirn-replacing operation may be caused to stop before the quantity of yarn on a supply package has become so depleted as to be insufficient to complete a further pirn, with the result that 25 careful checking of the completed pirns and/or the yarn supply package is rendered unnecessary. In addition, the machine operative is enabled to attend to a greater number of spindles.

30 The counting device may with advantage be operated by the pirn-replacing mechanism, a predetermined number of pirn replacements by the mechanism causing the device to operate to render the mechanism inoperative.

35 The counting device may comprise a rotatable member and driving means for rotating the member, the driving means being caused by the pirn-replacing mechanism to rotate the rotatable member through part of a revolution for each complete motion of the pirn-replacing mechanism. After rotating in this manner through a predetermined angle (i. e. after a predetermined number of pirn replacements have 40 been effected) the rotatable member may bring about the operation of the means for rendering the pirn-replacing mechanism inoperative.

The rotatable member may be a ratchet wheel adapted to be driven through part of a revolution by a pawl operated once for each complete motion of the pirn-replacing mechanism. Where the pirn-replacing mechanism comprises a replenishing member adapted to move at intervals to place an empty package support in winding 50 position, the pawl or other driving means may

conveniently be actuated by such replenishing member.

The device according to the invention may serve to stop the drive to the pirn-replacing mechanism so as to render such mechanism inoperative after the predetermined number of pirns have been wound. Thus, the device may operate a stop motion, or move a belt from a fast to a loose pulley to stop the drive, or may disengage the drive as by uncoupling a clutch. 10 Where the pirn-replacing mechanism is coupled to a source of power between each pirn-winding operation and thus set into motion to bring about pirn replacement, the device according to the invention may operate to prevent such coupling 15 after the predetermined number of pirns have been wound.

A convenient means for stopping the drive to the pirn-replacing mechanism comprises a latch controlled by the counting device and adapted to be moved by the device from an inoperative to an operative position to stop the drive after the predetermined number of pirns have been wound. The rotation of the rotatable member through a predetermined angle may cause the latch to be moved from an inoperative into the operative position and where the latch is remote from the rotatable member lever or like mechanism may connect the latch with the member. 20

The counting device according to the invention may be formed as a self-contained mechanism comprising the rotatable member, means for forming a driving connection between the pirn-replacing mechanism and the rotatable member and adapted to rotate the member through part of a revolution for each complete motion of the pirn-replacing mechanism, stopping means for rendering the pirn-replacing mechanism inoperative, and means forming a 25 connection between the rotatable member and the stopping means and adapted to actuate the stopping means on rotation of the rotatable member through an angle corresponding to a predetermined number of pirn-replacing motions. The device may comprise in addition means for permitting manual setting of the rotatable member in position to allow of the predetermined number of pirns to be wound before the actuation of the stopping means, and means 30 co-operating with the manually operated means for visually indicating the number of the pirns to be wound. Thus, a numbered device such as a disc or like member may be arranged to co-operate with the manually operated means to 35

55

give visual indication of the number of pirns to be wound.

The apparatus according to the invention may be incorporated in automatic pirn-winding machines of the type in which the pirns being wound are supported by spindles which pass through the pirn tubes or supports, and of the "spindleless" type, i. e., in which the pirns are supported by members which engage the ends 10 of the pirn tubes, the apparatus being particularly suitable for use in machines in which a single unit of pirn-replacing mechanism serves to replace a plurality of pirns at one time, a single counting device according to the invention 15 being capable of controlling such unit and consequently of determining the total number of pirns to be replaced thereby.

By way of example a form of apparatus according to the invention applied to an automatic 20 two-spindle pirn-winding machine described in U. S. application S. No. 140,630 filed May 4, 1937, will now be described in greater detail with reference to the accompanying diagrammatic drawings, of which:

25 Fig. 1 is a part cross-sectional end elevation of sufficient of the pirn-winding machine to illustrate the application of the invention thereto;

20 Fig. 2 is a part cross-sectional end elevation of the lower part of the machine viewed from the 30 right in Fig. 1;

Fig. 3 is a front elevation of part of the mechanism of Fig. 1 shown in larger scale and viewed along the line 3—3 of Fig. 5;

35 Fig. 4 is a front elevation of a further part of the mechanism of Fig. 1 shown in larger scale and viewed along the line 4—4 of Fig. 5; and

Fig. 5 is a plan of the details of Fig. 1 shown in Figs. 3 and 4.

Referring to Fig. 1 the pirn-winding machine 40 is of the well known type which comprises a gear box 6, clutch-driven winding spindles 7, and a starting rod 8 in association with each spindle. For simplicity of illustration one spindle 7 only is shown and the associated yarn traversing 45 mechanism is omitted. During winding yarn is traversed to and fro along part of the length of the pirn tube 9, the field of the traverse moving gradually from the base to the tip of the tube. On completion of the pirn stop mechanism operates to rotate the starting rod 8 to the inoperative 50 position so as to bring the spindles to rest, all in the manner well known to those skilled in the pirn-winding art.

On stoppage of the winding spindles 7 the completed pirns are automatically ejected from the spindles and replaced by fresh pirn tubes 9 on which the winding of new pirns continues, in the manner described in detail in the above-mentioned application, and briefly, as follows:

60 A sleeve 11 encircling the spindle 7 at a point between the base of the tube 9 and the gear box 6 is drawn along the spindle 7 towards its tip to eject the completed pirn therefrom by a toothed rod 12 which is slidably mounted in a sleeve 13 65 extending between the walls 14, 15 of the machine frame, the rod being driven by a pinion 16 which engages the teeth of the rod. The ejected pirn falls into a chute 10 leading to a collecting box or like container.

70 The entry of the rod 12 into the sleeve 13 causes a carriage 17 to be moved from a magazine (not shown) to a point opposite to the end of the now empty spindle 7, where a fresh pirn tube 9 carried by the carriage is pushed on to the spindle into winding position by a member 18, the sleeve

11 having been retracted to the position shown in the drawings, in the meantime, by reversal of the direction of rotation of the pinion 16. The member 18 is connected by an arm (not shown) to a toothed replenishing rod 19 slidably mounted in a sleeve 20 and driven by a pinion 21 engaging the teeth of the rod. Reversal of the rotation of the pinion 21 after the replenishing of the spindle 7 with the fresh pirn tube 9 causes the member 18 to be retracted by the replenishing rod 19 to the position shown in the drawings in readiness for further operation when required.

10 The pinions 16, 21 controlling the pirn-ejecting and spindle-replenishing rods 12, 19 are mounted on shafts 23, 24 which are driven by chains 25, 26 engaging sprockets (not shown) on the shafts. The chains 25, 26 are driven, respectively, by sprockets 27, 28 mounted on shafts 29, 30. Situated beneath the sprockets 27, 28 is a drum cam 32 freely mounted on a shaft 33. The surface 20 of the cam 32 is formed with two grooves 34, 35 in which are engaged pins 36 outstanding from two levers 37, 38. The levers 37, 38 engage by pin-and-slot connections, arms 39, 40 secured, respectively, to the shafts 29, 30. In this manner 25 rotation of the cam 32 brings about swinging of the levers 37, 38, first in one direction and then in the other, and, consequent operations of the toothed rods 12, 19 for the purposes described above.

30 The rotation of the cam 32 at the desired intervals is effected as follows:

Fixed to the shaft 33 closely adjacent to the right-hand end of the cam 32 is a disc 42 (see Figs. 1 and 2) having a plurality of semi-circular notches 43 formed on its periphery. The shaft 33 is driven by worm and wheel gearing 44, and the disc 42 thus rotates continuously.

35 A dog 45 freely pivoted on the end of the cam 32 normally rides idly on the periphery of the disc 42 and drops into and pulls out of the notches 43 as the disc rotates, the cam 32 remaining stationary on the rotating shaft 33. The dog 45 is under the control of a catch 46 also pivoted on the end of the cam 32 and urged by a spring 47 40 into anti-clockwise rotation (as seen in Fig. 2) 45 so as to engage the dog 45 and lock it in any notch 43 in order to couple the disc 42 with the cam 32, and thus initiate the pirn-ejecting and spindle-replenishing operation described above.

50 During winding, however, the catch 46 is restrained from dog-locking movement by a latch 48 pivoted on a spindle 49. The latch 48 is connected by a chain 50 to the end of a pin 52 slidably mounted in guides 53 formed at the head 55 of a lever 54 which is pivoted on a stub shaft 55 outstanding from the wall 15 of the machine frame (see Figs. 1, 4 and 5). The chain 50 passes through a stiff guiding pipe 56 which is secured to the machine frame at its ends by brackets 57 50 and 57'.

55 The end of the pin 52 is flattened to form a head 58, and a compression spring 59 encircles the pin between the head 58 and the guide 53. It will thus be apparent that when the lever 54 is held with its head 53 near to the head 58 of the pin 52 the spring 59 is compressed and subjects the chain 50 to tension with the result that the chain 50 forms a yieldable connection between the latch 48 and the lever 54, and tends to rotate 60 the latch clockwise about its pivot 49 and out of engagement with the catch 46. Conversely, when the lever 54 is freed to assume the position shown in Figs. 4 and 5, the tension in the spring 59 and chain 50 is relieved, and the latch 48 remains in

the position shown in Figs. 1, 2 and 4. During the normal winding operation of the machine, however, the spring 59 and chain 50 are maintained under tension, in a manner to be described later.

5 The tendency for the latch 48 to rotate under the influence of the tension in the chain 50 and thus free the catch 46 is restrained by the heads 60 of pivoted fingers 62, 63 (see Fig. 2), each of which is connected at 64 to a vertical rod 65 pivoted at its upper end to an arm 66 fixed to one of the spindle starting rods 8. On rotation of the starting rods 8 (clockwise as seen in Fig. 2) to stop their respective spindles 7 on completion 10 of the pirns the fingers 62, 63 are rotated about their pivots and free the latch 48 for rotation, under the influence of the tension in the chain 50, out of contact with the catch 46 to initiate the pirn-replacing operation described above.

15 20 If the two pirns are completed simultaneously both starting rods 8 rotate at the same time to stop the spindles 7 and move the respective fingers 62, 63 out of contact with the latch 48 which is thereupon freed to rotate from contact with the catch 46. If, however, one pirn is completed before the other, only the finger 62 or 63 in association with the completed pirn is moved out of engagement with the latch 48, the finger in association with the pirn still winding remaining 25 30 in the latch-pressing position until the latter pirn is completed, when the finger moves and allows the latch to rotate from catch-engaging position. In this manner danger of the drive to the pirn-replacing mechanism being established before a 35 pirn is completed, is avoided.

On completion of the pirn-replacing operation the continued rotation of the drum cam 32 brings a cam 67 formed at the end of the drum cam into engagement with a tappet lever 68 which is freely 40 pivoted at 69 to the machine frame. The tappet lever 68 is pushed upwardly by the cam and in so moving contacts with a horizontal bar 10 and pushes it into engagement with the lower ends of the two vertical rods 65 which are thereupon 45 moved upwardly to restart the winding spindles through starting rod 8. The bar 10 is supported in horizontal position by a pivoted arm 11. The upward movement of the vertical rods causes the fingers 62, 63 to rotate about their pivots into 50 engagement with the latch 48 which is thus depressed, against the tension in the chain 50, into the path of the catch 46. The catch is thereupon disengaged from contact with the dog 45 and the drive to the drum cam 32 is uncoupled.

55 The tension in the spring 59 and chain 50 is released by a counting device after a predetermined number of pirn-ejecting and spindle-replenishing operations, so as to render the drum cam 32 inoperative, in the following manner:

60 The head of the lever 54 (Figs. 4 and 5) is formed with a projecting member 12 which bears against the periphery of a disc 73 fixed on a rotatable shaft 74, the disc being partly cut away at 75 in a manner such that the head of the lever 54 can be held by the periphery of the disc either close to the head 58 of the pin 52 so as to compress the spring 59, or remote from the head 58 (as shown in Fig. 4) so as to release the pressure in the spring and consequently the tension in the chain 50, depending on which part 65 of the periphery of the disc is in contact with the projecting member 12.

The shaft 74 passes through the wall 15 and has secured thereto at the side of the wall remote from the disc 73 a toothed ratchet wheel 76

(Figs. 3 and 5) which is driven intermittently by a pawl 77 supported at the end of a lever 78 disposed between the wall 15 and the ratchet wheel 76, and adapted for free rotation about the shaft 74. The lever 78 is caused to oscillate to operate the pawl by a push rod 79 mounted in guides 80 and formed at its lower end with a cam portion 82.

The push rod is arranged so that the cam portion 82 projects across the end of the sleeve 20, 10 and a ram 83, formed on the end of the toothed spindle-replenishing rod 19, engages the cam and thereby pushes the rod and actuates the pawl on each return stroke of the toothed rod 19 after the replenishing of the associated spindle 7 with 15 a fresh pirn. In this manner the ratchet wheel 76, and consequently the disc 73, are rotated through a predetermined angle for each completed pirn-ejecting and spindle-replenishing operation.

The shaft 74 is furnished with a hand-controlling knob 84 by which the disc 73 can be rotated clockwise and set in any desired position relatively to the projection 72 at the head of the lever 54. In order to wind a predetermined number of pirns the disc 73 is rotated until the projection 72 at the head of the lever 54 bears against the notched portion of the periphery of the disc at the desired number of notches 85 away from the cut-away portion 75 corresponding to the predetermined number of pirn-ejecting and spindle-replenishing operations to take place before the rotation of the disc causes it to present its cut-away portion 75 to the projection 72 and thus free the lever 54 for clockwise rotation about the shaft 35 40 50 55 60 65 70 75 80 85 90 95 100 105 110 115 120 125 130 wards the notched portion in order to facilitate the re-setting of the disc.

The pirn counting mechanism according to the invention may be rendered inoperative by a hand lever 89 pivoted on the shaft 55 and formed with a flat projecting portion 90. On rotation of the lever 89 clockwise about the shaft 55 the portion 90 is caused to strike the head 58 of the pin 52 and push the pin to the right (as seen in Figs. 4 and 5) to release the tension in the chain 50. The effect of the movement of the hand lever 89 is thus the same as if the lever 54 had reached the cut-away portion 15 of the disc 13, and the latch 48 remains in catch-engaging position after the rotation of the starting rods 8 to stop the winding spindles 7. The hand lever 89 may be locked in the chain tension-relieving position.

Having described our invention what we desire to secure by Letters Patent is:

- 20 1. In a pirn winding apparatus incorporating mechanism for automatically doffing a completed pirn and donning an empty tube upon which the winding of a new pirn continues, driving means for said mechanism, a counting device adapted to be actuated by said mechanism at each doffing and donning operation, and means controlled by the counting device and adapted automatically to render the driving means for the doffing and donning mechanism inoperative after a predetermined number of pirns have been wound.
- 25 2. In a pirn winding apparatus incorporating mechanism for automatically doffing a completed pirn and donning an empty tube upon which the winding of a new pirn continues, driving means for said mechanism, a counting device adapted to be actuated by said mechanism at each doffing and donning operation, means controlled by the counting device and adapted automatically to render the driving means for the doffing and donning mechanism inoperative after a predetermined number of pirns have been wound.
- 30 3. In a pirn winding apparatus incorporating mechanism for automatically doffing a completed pirn and donning an empty tube upon which the winding of a new pirn continues, driving means for said mechanism, a counting device adapted to be actuated by said mechanism at each doffing and donning operation, means controlled by the counting device and adapted automatically to render the driving means for the doffing and donning mechanism inoperative after a predetermined number of pirns have been wound, and hand controlled means for the counting device to allow of an initial setting of the apparatus to any predetermined number of pirns that can be wound before the driving means for the doffing and donning mechanism is rendered inoperative.
- 35 4. In a pirn winding apparatus incorporating mechanism for automatically doffing a completed pirn and donning an empty tube upon which the winding of a new pirn continues, driving means for said mechanism, a counting device adapted to be actuated by said mechanism at each doffing and donning operation, means controlled by the counting device and adapted automatically to render the driving means for the doffing and donning mechanism inoperative after a predetermined number of pirns have been wound, hand controlled means for the counting device to allow of an initial setting of the apparatus to any predetermined number of pirns that can be wound before the doffing and donning mechanism is rendered inoperative, and means co-operating with the hand controlled means for visually indicating the number of pirns to be wound before the doffing and donning mechanism is rendered inoperative.
- 40 5. In a pirn winding apparatus incorporating mechanism for automatically doffing a completed pirn and donning an empty tube upon which the winding of a new pirn continues, driving means for said mechanism, a member for effecting the donning of an empty tube, a counting device adapted to be actuated by movement of said donning member at each doffing and donning operation, and means controlled by the counting device

and adapted automatically to render the driving means for the doffing and donning mechanism inoperative after a predetermined number of pirns have been wound.

5. In a pirn winding apparatus incorporating mechanism for automatically doffing a completed pirn and donning an empty tube upon which the winding of a new pirn continues, driving means for said mechanism, a member for effecting the donning of an empty tube, a counting device adapted to be actuated by movement of the donning member at each doffing and donning operation, said counting device comprising a rotatable member, and driving means for rotating said rotatable member, the latter driving means being caused by the donning member to rotate the rotatable member through part of a revolution for each complete motion of the donning member, and means controlled by the counting device and adapted automatically to render the driving means for the doffing and donning mechanism inoperative after a predetermined number of pirns have been wound.

6. In a pirn winding apparatus incorporating mechanism for automatically doffing a completed pirn and donning an empty tube upon which the winding of a new pirn continues, driving means for said mechanism, a member for effecting the donning of an empty tube, a counting device adapted to be actuated by movement of the donning member at each doffing and donning operation, said counting device comprising a ratchet wheel and a pawl for rotating the wheel, said pawl being caused by the donning member to rotate the ratchet wheel through part of a revolution for each complete motion of the donning member, and means controlled by the counting device and adapted automatically to render the driving means for the doffing and donning mechanism inoperative after a predetermined number of pirns have been wound.

7. In a pirn winding apparatus incorporating mechanism for automatically doffing a completed pirn and donning an empty tube upon which the winding of a new pirn continues, driving means for said mechanism, means for coupling the doffing and donning mechanism with the driving means between each pirn winding operation to bring about the doffing and donning operation, a counting device adapted to be actuated by said doffing and donning mechanism at each doffing and donning operation and means controlled by the counting device to prevent automatically such coupling after a predetermined number of pirns have been wound.

8. In a pirn winding apparatus incorporating mechanism for automatically doffing a completed pirn and donning an empty tube upon which the winding of a new pirn continues, driving means for said mechanism, means for coupling the doffing and donning mechanism with said driving means between each pirn winding operation to bring about the doffing and donning operation, a counting device adapted to be actuated by said doffing and donning mechanism at each doffing and donning operation and means controlled by the counting device comprising a latch adapted to be moved by the counting device into operative position to prevent the coupling of the doffing and donning mechanism with said driving means after a predetermined number of pirns have been wound.

9. In a pirn winding apparatus incorporating mechanism for automatically doffing a completed pirn and donning an empty tube upon which the

- winding of a new pирн continues, driving means for said mechanism, means for coupling the doffing and donning mechanism with said driving means between each pирн winding operation to bring about the doffing and donning operation, a member for effecting the donning of an empty tube, a counting device adapted to be actuated by movement of the donning member at each doffing and donning operation, said counting device comprising a rotatable member and driving means for rotating said member, the latter driving means being caused by the donning member to rotate the rotatable member through a predetermined angle for each complete motion of the donning member, and means controlled by the counting device comprising a latch adapted to be moved by the rotation of the rotatable member through said predetermined angle into operative position to prevent the coupling of the doffing and donning mechanism with the driving means therefor after a predetermined number of pирns have been wound.
10. In a pирн winding apparatus incorporating mechanism for automatically doffing a completed pирн and donning an empty tube upon which the winding of a new pирн continues, driving means for said mechanism, means for coupling the doffing and donning mechanism with said driving means between each pирн winding operation to bring about the doffing and donning operation, a member for effecting the donning of an empty tube, a counting device adapted to be actuated by movement of the donning member at each doffing and donning operation, said counting device comprising a rotatable member and driving means for rotating said member, the latter driving means being caused by the donning member to rotate the rotatable member through a predetermined angle for each complete motion of the donning member, and means controlled by the counting device comprising a latch remote from the rotatable member and a lever controlled by the rotatable member adapted to bring about the movement of the latch into operative position to prevent the coupling of the doffing and donning mechanism with the driving means therefor, after a predetermined number of pирns have been wound.
11. In a pирн winding apparatus incorporating mechanism for automatically doffing a completed pирн and donning an empty tube upon which the winding of a new pирн continues, driving means for said mechanism, means for coupling the doffing and donning mechanism with said driving means between each pирн winding operation to bring about the doffing and donning operation, a member for effecting the donning of an empty tube, a counting device adapted to be actuated by movement of the donning member at each doffing and donning operation, said counting device comprising a rotatable member and driving means for rotating said member, the latter driving means being caused by the donning member to rotate the rotatable member through a predetermined angle for each complete motion of the donning member, and means controlled by the counting device comprising a latch remote from the rotatable member, a lever controlled by the rotatable member, a member connecting the latch with the lever, a spring cooperating with the connecting member and the lever to render the connecting member yieldable, while maintaining such member at tension, and thereby tending to hold the latch in an inoperative position during the rotation of the rotatable member through the

predetermined angle, and means adapted on rotation of the rotatable member through the predetermined angle to free the lever for tension-relieving movement so as to permit the latch to move into operative position to prevent the coupling of the doffing and donning mechanism with the driving means therefor, after a predetermined number of pирns have been wound.

12. Apparatus according to claim 11, wherein the member connecting the latch with the lever is a chain.

13. Apparatus according to claim 11, comprising a pivoted finger under the control of the winding spindle starting rod of the pирн winding apparatus, said finger being rotated by the spindle starting movement of the rod and thereby caused to press the latch against the tension in the yieldable connecting member into operative position to prevent the coupling of the doffing and donning mechanism with the driving means therefor, and being rotated in the reverse direction by the spindle-stopping movement of the rod, so as to permit the latch to assume an inoperative position under the influence of the tension in the yieldable connecting member, in order to allow the coupling to be effected during the production of the predetermined number of pирns, the ultimate relieving of the tension in the yieldable connecting member causing the latch itself to move into operative position.

14. Apparatus according to claim 11, comprising a rotatable disc in driving engagement with the rotatable member, and having part of its periphery cut away, said disc being disposed in contact with the lever in a manner such that the uncut periphery of the disc holds the lever in a position in which the connecting member is held at tension and the cut part of the periphery frees the lever for movement into tension-relieving position when the rotation of the rotatable member causes the disc to present the cut-away part to the lever.

15. In a pирн winding apparatus incorporating mechanism for automatically doffing a completed pирн and donning an empty tube upon which the winding of a new pирн continues, driving means for said mechanism, means for coupling the doffing and donning mechanism with said driving means between each pирн winding operation to bring about the doffing and donning operation, a member for effecting the donning of an empty tube, a counting device adapted to be actuated by movement of the donning member at each doffing and donning operation, said counting device comprising a rotatable member and driving means for rotating said member, said latter driving means being caused by the donning member to rotate the rotatable member through a predetermined angle for each complete motion of the donning member, means controlled by the counting device for preventing coupling of the doffing and donning mechanism with the driving means therefor, after a predetermined number of pирns have been wound, said means comprising a latch remote from the rotatable member, a lever controlled by the rotatable member and adapted by the rotation of such member through the predetermined angle to bring about the movement of the latch into operative position to prevent the coupling between the donning and doffing mechanism and the driving means therefor, a member connecting the latch with the lever, a spring co-operating with the connecting member and the lever to render the connecting member yieldable while maintaining such member at

- 5 tension, and thereby tending to hold the latch in inoperative position during the rotation of the rotatable member through the predetermined angle, and means adapted on rotation of the rotatable member through the predetermined angle to free the lever for tension-relieving movement so as to permit the latch to move into said operative position, comprising a rotatable disc in driving engagement with the rotatable member and having part of its periphery cut away, said disc being disposed in contact with the lever in a manner such that the uncut periphery of the disc holds the lever in a position in which the connecting member is held at tension and the cut-away part of the periphery frees the lever for movement into tension-relieving position when the rotation of the rotatable member causes the disc to present the cut-away part to the lever, and hand-controlled means for the counting device to allow of an initial setting of the mechanism to any predetermined number of pirns that can be wound before the doffing and donning mechanism is rendered inoperative, comprising means for manually rotating the disc to set the cut part of its periphery in a position relatively to the lever such that the donning member can complete a predetermined number of complete motions before the rotation of the rotatable member causes the disc to present the cut-away part of its periphery to the lever.
- 10 16. Apparatus according to claim 15, wherein the uncut part of the periphery of the disc is formed with notches, each corresponding in extent to the angle of movement of the disc due to one complete doffing and donning operation.
- 15 17. Apparatus according to claim 15, comprising

ing a numbered plate in driving engagement with the disc and adapted to indicate the position of the cut-away part of the periphery of the disc relative to the lever and the number of doffing and donning operations which will be effected 5 before the doffing and donning mechanism is rendered inoperative.

18. A counting device for use in pirn winding apparatus incorporating mechanism for automatically doffing a completed pirn and donning 10 an empty tube upon which the winding of a new pirn continues, and stopping means for rendering such mechanism inoperative, said counting device comprising a rotatable member, driving means for the rotatable member and adapted 15 to be operated by the doffing and donning mechanism in a manner such that the driving means rotates the rotatable member through part of a revolution for each complete motion of the doffing and donning mechanism, and means forming 20 a connection between the rotatable member and the stopping means and adapted to operate said stopping means on rotation of the rotatable member through an angle corresponding to a predetermined number of doffing and donning 25 operations.

19. A counting device according to claim 18, comprising means for permitting manual setting of the rotatable member in position to allow of a predetermined number of pirns to be wound 30 before the actuation of the stopping means, and means co-operating with said manually-operated means for visually indicating the number of said pirns to be wound.
